KEY CASE

Frank Cannon, Rhinecliff, N. Y.

Application April 19, 1947, Serial No. 742,707

6 Claims. (Cl. 70—456)

1

The present invention relates to key cases, and has particular reference to a novel construction therefor.

The principal object of the invention is to form a key case out of stamped resilient sheet metal, the case parts being shaped to releasably grip the keys when within the case and when extended for use.

Another object of the invention is to form a key case with a belt or pocket clip which serves as an attaching or securing means, and also functions as a means for distinguishing between the ends of the key case, whereby the keys at each end of the case are identified.

An additional object of the invention is to construct a key case of resilient material, so shaped that it operates when pressed to release the keys from the key case into extended position and to freely receive the keys into the key case after use, to be spring held therein.

Still another object of the invention is to provide a simple key case construction which has no separate spring elements or other key holding parts, whereby the cost of manufacture is greatly reduced.

With the above and other objects and advantageous features in view, the invention consists of a novel arrangement of parts more fully disclosed in the detailed description following, in conjunction with the accompanying drawings, and more specifically defined in the claims appended thereto.

In the drawings:

Figure 1 is a perspective view of the novel key case, one key being shown in extended position ready for use;

Fig. 2 is a horizontal section on the line 2—2 of Fig. 1, showing one key held within the case and the extended key held in extended position;

Fig. 3 is a view similar to Fig. 2, both keys being shown housed in the case;

Fig. 4 is a view similar to Fig. 3, showing the release of a key at one end when the other end of the case is manually gripped; and

Fig. 5 is an enlarged perspective detail of one end of the case, disclosing the key gripping area at the end.

It has been found desirable to provide a key case in which two keys are housed, the case being of resilient material shaped to releasably hold the keys in place, but adapted when pressed to release either key for swinging to extended position and use, the key being releasably held in extended position until the case is again pressed, whereupon the extended key is released to swing

back into the case. To this end, I provide a key case preferably stamped out of resilient sheet metal stock in which two keys are pivotally secured, and which has one side shaped to function as a spring element for gripping the key ends between it and the other side, the end sections of the sides being movable towards each other when manually pressed to release the spring element pressure, whereby the key at the end which is not gripped may swing to extended position. The end sections of the sides are preferably shaped to grip the key which is extended, thus facilitating insertion of the key into a lock, the grip being released when the side sections at the opposite end are manually pressed together, whereupon the extended key may freely swing to be housed in the case.

Referring to the drawings, the novel key case 10 includes a housing 11 made of stamped resilient sheet metal, folded to provide two generally parallel sides 12, 13 which have their respective end sections 14, 15 and 16, 17 provided with inwardly extending circular bosses 18, 19, 20 and 21, the bosses 18 and 20 and 19 and 21 being aligned in slightly spaced relation to form split pivot posts 22, 23 for keys 24, 25. The keys are readily mounted on the pivot posts by slightly spreading the end sections, which resiliently close towards each other after the key opening is aligned with the circular bosses until the ends of the bosses are slightly spaced from each other.

The side 13 is dished at its central area, as indicated by the reference numeral 26, to provide a restricted space between it and the other side 12, whereby the key ends are gripped between the sides when the keys are housed in the case. The dishing operation preferably includes shearing a generally triangular clip 27 from the material of the side 13, thus increasing the resilience of the side 13 and providing a spring clip for releasably attaching the key case to a belt or garment part. The end 28 of the clip 27 is preferably curled, whereby the clip also functions as to tell-tale in darkness or dim light, to distinguish between the two ends and aid in selecting the desired key.

The end sections are shaped to releasably grip the shank of an extended key therebetween. As illustrated in Fig. 5 the end sections 14, 16 have their outer rounded portions partially indented or bent down as indicated by the reference numerals 29, 30, whereby the extended key, see Fig. 2, is resiliently clamped between the indented portions and is also slightly tilted and engages the side 12. Similarly, the housed key is gripped

between the two sides and is slightly tilted to engage its head with the end section of the side 13, as shown in Figs. 2 and 3.

When the two keys are housed in the case, as shown in Fig. 3, their ends are thus spring held, and their heads also resiliently engage the end sections of the side 13. When it is desired to release one key, the opposite end of the case is pressed, see Fig. 4; this causes the split post parts to contact each other and serve as a fulcrum to open the center and the other end of the case, releasing the key grip, whereby the key at the free end of the case may be readily swung to extended position by a quick hand snap. At this time, the hand pressure is released, whereupon the extended key now becomes spring held by the end clamp in extended position, ready for use. After the key is used, the opposite end is again pressed, whereupon the end clamp is released, and the key may swing back into the case, whereupon release of the pressing pressure again locks it in place in the case. The key at the pressed end cannot swing out, as the pressing pressure holds it in the case, as shown in Fig. 4.

The improved key case thus includes a unitary housing of stamped metal which is shaped to provide spring gripping of two keys when housed and when extended, and has a belt or garment clip, the clip serving as an indicator to distinguish between the two ends at night. The resilient central cupped portion of the sides carrying the clip not only releasably grips the outer ends of the two keys, but also keeps the two keys near the top of the case for quick release.

Further, the pivot supports for the keys are integral with the sides, act as spacing members for the sides, and also function as fulcrums when either end of the case is pressed, to spread the center area and the other end of the case for releasing the key at the other end. The end sections of the sides extend over the key ends when the keys are housed, and form pressure areas for obtaining the desired key releasing action; and also serve as gripping parts to hold an extended key in place, thus facilitating insertion of the key in the lock.

While I have described a specific embodiment of the invention, it is obvious that changes in the size, shape and material of the parts may be made to suit the requirements for different key cases, without departing from the spirit and the scope of the invention as defined in the appended claims.

I claim:

1. In a key case, a housing having two generally parallel sides, pivot means respectively intermediate each end and the center of the housing, each adapted to swingingly receive the head of a key thereon, means normally gripping the end of a key between said sides, and means whereby pressing either end of the housing beyond the pivot means releases the key end gripping means.

2. In a key case, a housing having two generally parallel sides, pivot means respectively intermediate each end and the center of the housing, each adapted to swingingly receive the head of a key thereon, means normally gripping the end of a key between said sides, means at each end of the housing normally gripping the shank of

a key when it is swung to extended position beyond the housing end, and means whereby pressing either end of the housing beyond the pivot means releases the key end gripping means and the key shank gripping means at the other end of the housing.

3. In a key case, a housing having two generally parallel sides, pivot means respectively intermediate each end and the center of the housing, each adapted to swingingly receive the head of a key thereon, means normally gripping the end of a key between said sides, and means whereby pressing either end of the housing beyond the pivot means releases the key end gripping means, said pivot means including spaced aligned pivot parts extending inwardly from each side.

4. In a key case, a housing having two generally parallel sides, pivot means respectively intermediate each end and the center of the housing, each adapted to swingingly receive the head of a key thereon, means normally gripping the end of a key between said sides, means at each end of the housing normally gripping the shank of a key when it is swung to extended position beyond the housing end, and means whereby pressing either end of the housing beyond the pivot means releases the key end gripping means and the key shank gripping means at the other end of the housing, said pivot means including spaced aligned pivot parts extending inwardly from each side.

5. In a key case, a housing having two generally parallel sides, pivot means respectively intermediate each end and the center of the housing, each adapted to swingingly receive the head of a key thereon, means normally gripping the end of a key between said sides, and means whereby pressing either end of the housing beyond the pivot means releases the key end gripping means, said end gripping means including a resilient portion of one side extending towards the other side.

6. In a key case, a housing having two generally parallel sides, one of said sides being of resilient material, said sides each having a pivot part adjacent each end, the pivot parts adjacent each end being in spaced alignment and forming a split pivot post for swingingly receiving the head of a key, said resilient side having a central portion extending towards the other side to grip the ends of keys mounted on the split pivot posts, the ends of the sides beyond the split pivot posts being manually pressable towards each other, whereby pressure on said side ends at either end of the housing contacts the pivot post parts at that end to form a fulcrum for shifting said central portion to key end releasing position.
